UNITED STATES PATENT OFFICE.

HENNING FRIEDRICH WALLMANN, OF CHICAGO, ILLINOIS.

GAS-PRODUCER.

1,072,536.

Specification of Letters Patent.

Patented Sept. 9, 1913.

Application filed July 21, 1906, Serial No. 327,229. Renewed January 3, 1911. Serial No. 600,642.

To all whom it may concern:

Be it known that I, HENNING FRIEDRICH WALLMANN, a citizen of the United States, residing at Chicago, in the county of Cook 5 and State of Illinois, have invented a new and useful Counter-Current Gas-Producer, of which the following is a description, reference being had to the accompanying drawings, forming a part of this specification, in 10 which similar letters and figures indicate like parts.

My invention relates to gas producers and more particularly to that type of gas producers in which an air current passes 15 through a quantity of fuel such as coal, coke, wood, lignite, or peat, etc., and in burning a part of the same produces heat, thereby gasifying the rest of the fuel; and the objects of my invention are, first, to utilize 20 as great as possible a part of the generated heat for the gasifying of the fuel; second, to heat the generated gases and vapors to a very high temperature in order to convert any condensable vapors into permanent 25 gases; third, to arrange in the gas producer vessel two fire places, one of which is used for generating heat for the purpose of evaporating the volatile substance in the fuel, whereas the other fire-place is used for simultaneously 30 heating the generated vapors in order to convert the same into permanent, fixed gases, and to preferably provide the said two fire-places with means for exchanging their functions against each other from time to time; fourth, to promote a current of gases from one of the said fire places to the other and to provide means for controlling and for preferably reversing the said current of gases from time to time; fifth, to provide an automatic device 40 for reversing the said current of gases at certain periods with the aid of a device for keeping the time of such periods; sixth, to facilitate the passage of the gases from one fire place to the other in the case that the fuel cakes and offers obstruction to the passage of air or gases through it; and seventh, to provide outlet ports for the discharge of fuel after its volatile parts have been gasified. 45 This construction, however, is only applied in the case that the gas producer is intended to produce also coke in combination with gas. I attain these objects by the apparatus illustrated in the accompanying drawings, in which—

Figure 1 is a vertical section through the

gas producer vessel; Fig. 2 is a diagrammatical view of the valve controlling device; Fig. 3 is a section through air passages provided between the two fire places, and Fig. 4 is a vertical section of a gas producer construction modified with the object of combining the production of coke with that of gas.

I use in this gas-producer preferably bituminous coal, and the construction of the gas-producer is for the greatest part determined by the nature of bituminous coal. If the latter is heated, it bakes, clogs, increases in volume and becomes almost impenetrable for an air current. But after its volatile substance has been evaporated or gasified, it is porous and may be easily penetrated by an air- or gas-current. If a pile of bituminous coal is heated from its base, and the volatile substance of its lowest layer evaporated, then a current of air may pass in horizontal direction through this lowest layer of the coal-pile, which lowest layer actually consists of porous coke. The air-current, in passing through this porous incandescent coke in horizontal direction, burns the coke and in generating heat, evaporates the volatile substance above. In the same degree as the solid material at the base of the pile is thus consumed, the rest of the pile is lowered by its own gravity. This process which is embodied in my gas-producer employs a horizontal air- and gas-current contrary to all known gas-producers in which up- and down-currents are used. Means for removing the ashes and clinkers and means for converting the generated vapors into permanent gases are combined with the horizontal air- and gas-current and modify in some degree the direction of the current.

The gas producer is preferably made of cast iron lined in its very hot parts with fire-proof material *m*, *m*.

10 is an air supply pipe leading air, and in some cases also steam, through one of the valve controlled conduits 11 or 12 to the fire grates 13 or 14 respectively, and also through one of the chambers 15 or 16 and 105 the holes 17 or 18, to the fire places *F*₁ or *F*₂ situated on top of the grates 13 and 14 respectively and in the lower part of the fuel chamber *H* of the gas producer. The latter is provided at its top with a funnel or hopper *h* which may be of any well known construction, although it is desirable that fuel

can be supplied into the fuel chamber H without the latter being at any time in open communication through the hopper h with the open air outside of the gas producer.

5 19 and 20 are outlet openings for the generated gas. They take the gas directly from the fire places, but are placed at such a distance between and from the grates and the air supply openings 17 and 18 as to effect 10 a chemical union of the oxygen of the air with the incandescent fuel of the fire places before any air from the said air sources can enter into the gas outlets 19 or 20. The latter enter into the chambers 21 and 22 respectively, each of which chambers forms 15 a closed jacket around one of the fire-hearths F₁ and F₂ respectively by surrounding the same in all horizontal directions, as indicated by dotted lines 5 and 6 in the drawing, and communicates through one of the valve-controlled conduits 23 and 24 respectively with the gas-outlet 25. The chambers 20 21 and 22 are separated from each other by a partition 9. 25 26, 26 are rods which, by being turned or moved up and down, may be used for breaking up the fuel in the case that it cakes. The front and rear walls 27 of the fuel chamber H, (Fig. 3) are provided with suitable 30 projections 28, forming ducts below them and facilitating the flow of the gases to the gas-outlet-openings of either fire-hearth. Such ducts or canals may also be formed in the fire-clay-lining m especially 35 of large gas-producers, whereas such ducts or canals may be omitted especially in gas-producers of smaller dimensions. The chambers 15 and 16 inclose the chambers 21 and 22 respectively, as is indicated by the dotted lines 7, 7 in the drawing, and may 40 communicate with each other through the narrow holes 8, 8, the area of which may be made adjustable. The gas issuing from one of the fire places heats the wall between the said chambers, which wall heats in turn the entering air. The amount of air entering 45 through the air supply openings 17 and 18 may be regulated by registers 29 and 30. Each of the four conduits 11, 12, 23 and 24 may be closed by one of the valves v₁, v₂, 50 v₃, and v₄ respectively, which valves are connected to and moved by a shaft L, but are to a certain extent movable on the said shaft. Springs s₁ and s₂ have a tension to 55 keep apart the valves v₁ and v₂, as well as v₃ and v₄ as far as the buffers or stops C allow, namely, as far as to allow a simultaneous closing of all four conduits 11, 12, 23 and 24, and as far as to prevent the two air supply 60 conduits 11 and 12, as well as the two gas outlet conduits 23 and 24, being open at the same time. Whenever the conduits 11 and 24 are intended to be closed, the shaft L is turned in a direction opposite from the direction in which the hand of a watch turns.

At the beginning of the turning movement the valves v₂ and v₃ keep the conduits 12 and 23 closed until the valves v₁ and v₄ have closed the conduits 11 and 24, and until the valves v₂ and v₃ are removed from their seats by their respective buffers or stops C. It is not necessary to apply the ends of the springs s directly to the back of the valves. In order to protect the springs against heat, the valve may be connected to sleeves or tubes inclosing the shaft L and remote springs may act by means of such sleeves or tubes on the valves.

As long as air is supplied to a certain fire place of the two, its temperature increases, or may remain constant after it has attained a certain height, whereas the other fire place by imparting heat to the generated vapors, gradually loses its heat. In order to keep the temperature of the latter fire-place at substantially the same height, some air may be introduced through the narrow holes 8, 8, the upper-air-inlet-opening and the grate of this fire-place, thereby generating about just as much heat as is absorbed by the said vapors. This introduction of air into the second fire-place may be applied especially in gas-producers of large dimensions, as there is danger in gas-producers of small dimensions that some unburnt oxygen or 95 some carbon-dioxid escapes with the gas before being reduced to carbon-monoxid. In any case the amount of air introduced into the second fire-hearth should be limited, and in the case that the vapors absorb more heat 100 than is generated by the entering air, and if in consequence thereof the temperature of the second fire-hearth unduly decreases, or if the chambers 15 and 16 are separated from each other by a partition without any 105 holes in the same way as the chambers 21 and 22, and are without any communication except through the fuel-chamber H and through the valve-controlled conduits 11 and 12, the narrow holes 8, 8 being closed, the 110 current of air and gases may be reversed from time to time by turning the shaft L in one direction or the other. This may be done by hand or it may be done automatically. In Fig. 2 the shaft L is connected 115 by means of the crank 31 and by means of connecting- and piston-rods to the piston in the cylinder 32, which may be connected by means of pipes and an auxiliary or pilot valve 33 to a source of fluid under pressure 120 34, as well as to an exhaust or discharge pipe 35. A source of electricity 36 may be automatically connected by means of a time keeping machine 37 to a solenoid 38, which, by moving the auxiliary valve 33, causes a 125 stroke of the piston in the cylinder 32 and turns the shaft L for a certain angle, enough to close two of the valves v₁, v₂, v₃ and v₄, and to open the two others. After 130 a certain space of time, say five minutes, has

elapsed, the time keeping machine automatically reverses the electric circuit and indirectly reverses thereby the air and gas current in the gas producer, as will be understood by any mechanic. As time keeping machine may be employed an engine, of which the crankshaft makes a certain number of revolutions per hour and the time keeping machine may eventually directly operate the auxiliary valve 33 or the shaft L of the main-valve-mechanism. In the case that the gas is used for a reversible gas engine which is provided with an air pump and air tank, the motive power for operating the cylinder 32 may be to advantage supplied by means of compressed air.

In Fig. 4 the two fire places F_1 and F_2 are removed to a greater distance from each other, and between the two hoppers h_1 and h_2 is placed another hopper h_3 , and below same a discharge port 39 for the discharge of coke. The operation of this gas producer is exactly that of the gas producer shown in Fig. 1, the only difference being that some bituminous coal is introduced into its fuel chamber through the hopper h_3 and is discharged through the port 39 after its volatile matter has been gasified by the heat of the hot gases produced by the two fire places F_1 and F_2 .

The bituminous fuel in the center part of the gas producer in Fig. 4 may be separated by perforated partitions or walls w_1 and w_2 from the two fire places F_1 and F_2 respectively, and the coke discharged from the center part through the port 39 may afterward be supplied into the hoppers h_1 and h_2 in order to entertain the fire at the fire places F_1 and F_2 .

The air current in my countercurrent producer may be either the result of means for pressing air into the air supply pipe 10, or may be the result of means for drawing the gas out of the gas outlet pipe 25. In each case the gas may pass through a scrubber and other apparatus for cleaning it. The air may also be mixed with steam and the surplus of heat may be utilized in the same way as is done in other gas producers in which the heat of the discharged gas, for instance, is imparted to a boiler or to a regenerator. Also the air supply may be stopped entirely for some time after the fire places F_1 and F_2 are sufficiently hot, and steam only, or steam and liquid fuel (crude oil), or liquid fuel only, may be introduced into one and later into the other of the two fire places. They may there be decomposed into permanent gases, carry the heat to the center portion of the fuel chamber, gasify the volatile matter at this place, and flow with the generated gases and vapors to the second fire place where any condensable vapors are converted into permanent gases. This process may be carried

on as long as the fire places F_1 and F_2 are hot enough. As soon as their temperature becomes too much reduced, the process has to be interrupted and air has to be blown for some time into the fire places in order to raise the heat therein again. As stated before, the heat of the generated gases may be indirectly transferred into the air in the chambers 15 and 16, but as this transference is only incomplete, the gases arrive in a hot state in the outlet pipe 25 and the gases may to great advantage be used for preparatorily heating the air before entering the ash pits below the grates 13 and 14.

I claim—

1. In a gas-producer, two combustion-chambers for consuming residue of previous distillation, a distillation-chamber for distilling fuel and for supplying residue of distillation to the said two combustion-chambers, and canals in communication with the said two combustion-chambers and in conjunction with means for alternately and periodically transporting gaseous products of combustion from one and from the other of the said two combustion-chambers for the purpose of supplying latent heat to fuel under distillation within the said distillation-chamber.

2. In a gas-producer, a fire-proof-lined combustion chamber for consuming residue of previous distillation, a distillation chamber with metal walls for distilling fuel and for supplying residue of distillation to the said combustion-chamber, and two conduits with walls partly integral with the metal walls of the said distillation-chamber and in communication with this chamber and in conjunction with means for transporting a heat carrying fluid containing substantially no free oxygen into immediate contact with fuel in the said distillation chamber and for transporting distillates into incandescent residue of distillation.

3. In a gas producer, two producer shafts for secondarily distilling residue of primary distillation and for gasifying residue of secondary distillation and each provided with an upper and a lower air inlet and with an intermediate gas outlet and with an inlet for distillates, a distillation chamber for primarily distilling fuel and for supplying residue of distillation to one of the said producer shafts, and a canal in communication with the said distillation chamber and with the said inlet for distillates of each of the said two producer shafts and in conjunction with means for discharging distillates from the said distillation chamber alternately into one and into the other of the said two producer shafts.

4. In a gas producer, a producer shaft for secondarily distilling residue of primary distillation and for gasifying residue of secondary distillation and provided with a

- lower and an upper air inlet and with an intermediate gas outlet, a distillation chamber for primarily distilling fuel and for supplying residue of distillation to the said producer shaft, a plurality of canals in proximity to fuel within the said distillation chamber and in communication with the said producer shaft for transferring heat from residue of distillation within the said producer shaft to fuel within the said distillation chamber, and means for discharging distillates from the said distillation chamber.
5. In a gas producer, a fire-proof lined producer shaft for secondarily distilling residue of primary distillation and for gasifying residue of secondary distillation and provided with a lower and an upper air inlet and with an intermediate gas outlet, a distillation chamber with metal walls above the said producer shaft for primarily distilling fuel and for supplying residue of distillation to the said producer shaft, and a plurality of canals with walls partly integral with the metal walls of the said distillation chamber and in communication with the said producer shaft for transferring heat from the latter to fuel within the said distillation chamber.
10. In a gas-producer, a retort for distilling solid fuel, two combustion chambers for consuming residue of distillation, a plurality of conduits for discharging gases from either combustion-chamber past the said retort and for discharging distillates from the said retort into either combustion chamber, and walls for preventing solid fuel within the said retort from entering into the said conduits.
15. In a gas-producer, a retort for distilling solid fuel, two combustion-chambers for consuming residue of distillation, a plurality of conduits for discharging gases from either combustion-chamber past the said retort and for discharging distillates from the said retort into either combustion-chamber, and inlets for supplying oxygen to the distillates in either combustion-chamber.
20. In a gas-producer, a retort for distilling solid fuel, two combustion chambers for consuming residue of distillation, a plurality of conduits for discharging gases from either combustion-chamber past the said retort and for discharging distillates from the said retort into either combustion chamber, and walls for preventing solid fuel within the said retort from entering into the said conduits.
25. In a gas-producer, a retort for distilling solid fuel, two combustion chambers for consuming residue of distillation, a plurality of conduits for discharging gases from either combustion-chamber past the said retort and for discharging distillates from the said retort into either combustion chamber, and walls for preventing solid fuel within the said retort from entering into the said conduits.
30. In a gas-producer, a retort for distilling solid fuel, two combustion chambers for consuming residue of distillation, a plurality of conduits for discharging gases from either combustion-chamber past the said retort and for discharging distillates from the said retort into either combustion chamber, and walls for preventing solid fuel within the said retort from entering into the said conduits.
35. In a gas-producer, a retort for distilling solid fuel, two combustion chambers for consuming residue of distillation, a plurality of conduits for discharging gases from either combustion-chamber past the said retort and for discharging distillates from the said retort into either combustion chamber, and inlets for supplying oxygen to the distillates in either combustion-chamber.
40. In a gas-producer, a retort for distilling solid fuel, two combustion chambers for consuming residue of distillation, a plurality of conduits for discharging gases from either combustion-chamber past the said retort and for discharging distillates from the said retort into either combustion chamber, and walls for preventing solid fuel within the said retort from entering into the said conduits, and a valve mechanism for alternately discharging distillates from one and from the other of the said two combustion chambers.
45. In a gas-producer, a retort for distilling solid fuel, two combustion chambers for consuming residue of distillation, a plurality of conduits for discharging gases from either combustion-chamber past the said retort and for discharging distillates from the said retort into either combustion chamber, and walls for preventing solid fuel within the said retort from entering into the said conduits, and a valve mechanism for alternately discharging distillates from one and from the other of the said two combustion chambers.
50. In a gas-producer, a retort for distilling solid fuel, two combustion chambers for consuming residue of distillation, a plurality of conduits for discharging gases from either combustion-chamber past the said retort and for delivering distillates from the said retort into either combustion chamber, walls for preventing solid fuel within the said retort from entering into the said conduits, and a valve mechanism for alternately discharging distillates from one and from the other of the said two combustion chambers.
55. In a gas-producer, a retort for distilling solid fuel, two combustion chambers for consuming residue of distillation, a plurality of conduits for discharging gases from either combustion-chamber past the said retort and for delivering distillates from the said retort into either combustion chamber, walls for preventing solid fuel within the said retort from entering into the said conduits, and a valve mechanism for alternately discharging distillates from one and from the other of the said two combustion chambers.
60. In a gas-producer, a retort for distilling solid fuel, two combustion chambers for consuming residue of distillation, a plurality of conduits for discharging gases from either combustion-chamber past the said retort and for delivering distillates from the said retort into either combustion chamber, walls for preventing solid fuel within the said retort from entering into the said conduits, and a valve mechanism for alternately discharging distillates from one and from the other of the said two combustion chambers.
65. In a gas-producer, a retort for distilling solid fuel, two combustion chambers for consuming residue of distillation, a plurality of conduits for discharging gases from either combustion-chamber past the said retort and for delivering distillates from the said retort into either combustion chamber, walls for preventing solid fuel within the said retort from entering into the said conduits, and a valve mechanism for alternately discharging distillates from one and from the other of the said two combustion chambers.

70. rality of conduits for discharging gases from either combustion chamber past the said retort and for delivering distillates from the said retort into either combustion chamber, inlets for supplying oxygen to the distillates in either combustion chamber, and a valve mechanism for alternately discharging distillates from one and from the other of the said two combustion chambers.

75. 10. In a gas producer, a fire-proof lined producer shaft for secondarily distilling residue of primary distillation and for gasifying residue of secondary distillation and provided with a lower and an upper air inlet and with an intermediate gas outlet, a metal walled distillation chamber for primarily distilling fuel above the said producer shaft and constructed to supply residue of distillation thereinto, a conduit constructed to heat fuel within the said distillation chamber, and a conduit free of solid fuel inside of the said distillation chamber for the passage of fluid.

80. 11. In a gas producer, a fire-proof lined producer shaft for secondarily distilling residue of primary distillation and for gasifying residue of secondary distillation and provided with a lower and an upper air inlet and with an intermediate gas outlet, a metal walled distillation chamber for primarily distilling fuel above the said producer shaft and constructed to supply residue of distillation thereinto, a conduit for transferring heat from residue of distillation within the said producer shaft to fuel within said distillation chamber, and a conduit in communication with the said distillation chamber and partly inclosed by the metal wall thereof and free of solid fuel for the passage of fluid.

85. 12. In a gas producer, two producer shafts side by side each constructed to gasify solid fuel, two separate conduits provided for each of the said producer-shafts, one of the 110 said two conduits provided with an air inlet communicating through a lower and the other of the said conduits provided with a gas outlet communicating through an upper opening with the appertaining producer 115 shaft, the distance between the said two openings in elevation being sufficient for effecting a different state of combustion of the fuel in front of one with respect to the fuel in front of the other of the said two 120 openings, a communication connecting the upper parts of the said two producer shafts, and a valve mechanism adapted to alternately deliver gas from the gas-outlet of one and from that of the other of the said 125 two producer-shafts for thereby producing oppositely directed gas-currents through the said communication.

90. 13. In a gas producer, two producer shafts, an air-inlet into and a gas-outlet out 130

of each of the said producer-shafts, a distillation-chamber above the said two producer shafts and in communication therewith for a supply of residue of distillation thereinto, a conduit, free of solid fuel, and forming a communication connecting the said two producer shafts to each other past the said distillation chamber and constructed to transfer heat from residue of distillation within either of the said two producer shafts to fuel within the said distillation chamber, and a valve mechanism adapted to alternately deliver gas from the gas-outlet of one and from that of the other of the said two producer-shafts for thereby producing oppositely directed gas currents.

14. In a gas producer, two fire proof lined producer-shafts side by side, an air-inlet into and a gas-outlet above said air inlet out of each of the said producer shafts, a metal walled distillation-chamber above the said two producer-shafts and in communication therewith for a supply of residue of distillation thereinto, a metal walled conduit, free of solid fuel, and forming a communication connecting the said two producer-shafts to each other past the said distillation chamber and constructed to trans-

fer heat from residue of distillation within either of the said two producer-shafts to fuel within the said distillation chamber, and a valve mechanism adapted to alternately deliver gas from the gas outlet of one and from that of the other of the said two producer shafts for thereby producing oppositely directed gas currents in the said conduit.

15. In a gas producer, a fire-proof lined producer shaft for gasifying residue of distillation and provided with a lower and an upper air inlet and with an intermediate gas outlet, a metal walled distillation chamber for distilling solid fuel above the said upper air inlet and constructed to convey residue of distillation toward the said producer shaft, a conduit constructed to heat solid fuel within said chamber by means of gaseous products of combustion, and a conduit free of solid fuel within said chamber and communicating therewith and constructed to deliver distillates therefrom into the upper part of said producer shaft.
